FOREIGN PATENT DOCUMENTS

WO 2011140533 11/2011

Primary Examiner — Elizabeth A. Albert(74) *Attorney, Agent, or Firm* — Michael Best & Friedrich LLP(57) **CLAIM**

We claim the ornamental design for a saw blade, as shown and described.

DESCRIPTION

FIG. 1 is a perspective view of a saw blade showing my new design.

FIG. 2 is a side view of the saw blade of FIG. 1.

FIG. 3 is a first end view of the saw blade of FIG. 1.

FIG. 4 is a second end view of the saw blade of FIG. 1.

FIG. 5 is a top view of the saw blade of FIG. 1; and,

FIG. 6 is a bottom view of the saw blade of FIG. 1.

The broken away symbols in the drawings indicate the appearance of any portion of the article between the break lines forms no part of the claimed design.

1 Claim, 3 Drawing Sheets(56)
